SHELL-BANDING MACHINE

Axel F. Rehnberg, Rockford, Ill., and John Nelson, Santa Monica, Calif., assignors to Rehnberg-Jacobson Mfg. Co., Inc., Rockford, Ill., a corporation of Illinois

Application January 18, 1943, Serial No. 472,740

3 Claims. (Cl. 78—15)

1

This invention relates to a new and improved shell-banding machine.

The copper rifling band, which is larger in diameter than the shell and must be entered with a tight fit in an annular groove in the shell, and firmly held against turning by tight engagement with serrations in the groove, has heretofore been slipped over the shell to the groove and then in one operation compressed by a number of slides moving radially inwardly so as to cause the band to enter the groove and grip the serrations. It has been found that there were too many rejections of shells banded in that way, due to crystallization of the metal in the band. It is, therefore, one of the principal objects of our invention to provide a shell-banding machine in which, the band is compressed only very slightly in the first operation and is thereafter indexed before the next heavier compression, there being preferably a number of subsequent compressions with automatic indexing between compressions to permit uniform metal flow, prevent crystallization of the copper, and provide thorough penetration into the serrations.

Another object of our invention is to provide a machine of the kind mentioned in which movement of the jaws for the first squeeze is positively limited for a partial squeeze, sufficient only to allow the ring into engagement with the tips of the serrations, the jaws in the subsequent squeezes being controlled only as to the pressure applied, the shell being turned slightly between these various operations, as previously stated, so that after the last squeeze the band is certain of being swaged solidly in place in the groove and the metal of the band having flown uniformly is not apt to be crystallized.

Another object of our invention is to provide a machine of the kind mentioned, in which the plurality of jaws movable radially inwardly for compression of the band onto the shell are all operated by a single ram movable axially, the jaws being on lever members swingable inwardly along radial lines, and the ram being centrally arranged on the vertical axis of the machine and operated hydraulically by a single piston and cylinder to operate the jaws by oscillation of their lever members, whereby to secure maximum compactness, simplicity, and economy of construction.

Still another object of our invention is to provide a machine of the kind mentioned which may be quickly and easily changed to handle all sizes of projectiles, from 20 mm. to and including 75 mm., either armor piercing or high explosive

2

types, the change-over from one size to another being mainly only a matter of substituting a different set of jaws, the jaws being removably secured to the inner ends of slides actuated by the lever members.

Still another object of our invention is to provide a machine of the kind mentioned, in which a mandrel is provided for entry into the bore of high explosive type shells for support of the wall thereof in the vicinity of the band receiving groove, so that there will be no danger of distortion of the shell in the application of the band.

The invention is illustrated in the accompanying drawings, in which:

Fig. 1 is a side view of a machine made in accordance with our invention;

Figs. 2, 3, and 4 are views of the butt portion of a shell showing the band in section before application, at an intermediate stage of application, and as finally applied;

Figs. 5 and 6 are cross-sections on the lines 5—5 and 6—6 of Figs. 3 and 4, respectively;

Fig. 7 is a central vertical section through the machine illustrating the relationship of the ram to the lever members which operate the band compressing jaws;

Fig. 8 is a top view of the machine with a portion of the cover broken away to better illustrate the construction;

Fig. 9 is a fragmentary vertical section on the broken line 9—9 of Fig. 8;

Fig. 10 is an enlarged sectional detail taken on the line 10—10 of Fig. 9;

Fig. 11 is a view similar to Fig. 10 showing the parts in a moved position;

Fig. 12 is an electrical and hydraulic circuit diagram of the machine, and

Fig. 13 is a fragmentary vertical section of another machine, illustrating the mandrel for support of the thin walls of high explosive type shells.

Similar reference numerals are applied to corresponding parts throughout the views.

Referring first to Figs. 2 to 6, the reference numeral 5 designates a shell and B the copper rifling band therefor. Each shell is provided with an annular groove 14 near the butt end to receive the band, and has rings of serrations 15 formed in the groove to grip the band and prevent turning thereof when the band has been applied. The band before application is larger in diameter than the shell so that it can be slipped easily over the shell to the groove, as illustrated in Fig. 2. Then, in accordance with

our invention, the band is given a partial squeeze to flow the band only to the top of the serrations, as illustrated in Figs. 3 and 5, the circumferentially spaced protruding portions 16 on the periphery of the band being what may be termed flash, that being the metal in the spaces between the jaws. In this partial squeeze the band has taken hold of the serrations well enough to insure the band turning with the shell in the indexing of the latter between squeezes, in accordance with our invention. The shell with the band thus partially applied is indexed so that the projecting flash portions 16 on the band will be compressed by the jaws in the next squeeze, which is a heavier squeeze and may or may not be the final squeeze. Usually, however, there is one light partial squeeze and two heavy squeezes, and, as will soon appear, the machine herein illustrated is constructed for such operation. The indexing of the shell between squeezes permits uniform metal flow, prevents crystallization of the copper, and provides thorough penetration into the serrations. The band as it appears when finally applied is illustrated in Figs. 4 and 6.

The machine, as illustrated in Figs. 1, 7, 8, and 9, comprises a hollow base 17, on the top of which is supported a spider-shaped casting 18, providing five radial guides 19 in equally spaced relation for the same number of slides 20 which operate the band compressing jaws 21. Each slide has a cooperating lever member 22 pivoted intermediate its ends, as at 23, on the spider 18 and operatively connected with the slide at its bifurcated upper end 24 in which a block 25 is slidably received, the block being pivoted on a crosspin 26 on the slide. A cradle 27 is suspended from the spider 18 within the base 17 and has spring pressed plungers 28 mounted in the side walls thereof engaging the levers 22 near the lower ends, so as to keep the shoes 29, which are pivoted on the lower ends of the levers, as at 30, in close working contact with wedge blocks 31 demountably secured on the flat faces 32 of the ram 33. The ram is internally threaded at 34 for adjustable threaded connection with the upper end of a piston rod 35, a nut 36 threaded on the rod being tightened against the bottom of the ram to lock it in adjusted position. The cradle 27 supports a hydraulic cylinder 37 in which a piston 38 on the lower end of the rod 35 operates. Pipes, indicated at 39, are for inlet and outlet of oil to and from the opposite ends of the cylinder. As will presently appear, oil is delivered under pressure to the lower end of the cylinder 37 to raise the piston 38 and ram 33 to cause the jaws 21 to move radially inwardly toward one another and thereby compress the band B on the shell S. In the first squeeze the length of the stroke of the piston and ram is regulated, as will later appear, so that the band is compressed only to the point of engagement with the serrations 15 in the groove 14 on the shell, so as to be held against turning with respect to the shell, but in the subsequent squeezes there is no regulation of the stroke but only regulation of the pressure applied by the jaws. That is to say, the jaws are permitted in the second and third squeezes to apply pressure to the band until the pressure in the cylinder 37 builds up to a predetermined amount, whereupon the pressure is released and oil under pressure is delivered to the upper end of the cylinder 37 for return of the ram 33.

The ram 33 is guided at circumferentially

spaced points by segmental-shaped bearings 40 projecting radially inwardly from the side walls of the cradle 27 between the wedge blocks 31. A plate 41 is removably secured on the upper end of the ram 33 and has the lower end of a rod 42 adjustably and detachably connected therewith, as indicated at 43. This rod is reciprocable in a vertical guide 44 provided therefor in the spider 18 and has rack teeth 45 provided on one side of the upper end portion thereof for meshing engagement with a pinion 46. This pinion is part of a cluster with the larger gear 47, which meshes with the rack 48, horizontally disposed and slideable freely in a guide 49 on top of the spider 18. The rack 48 has rack teeth 50 on one side of the other end thereof remote from the gear cluster 46-47 meshing with a gear 51 formed on a hub 52, in which a spring pressed pawl 53 is slidably mounted for cooperation with the teeth of a ratchet wheel 54 secured on the upper end of a tubular shaft 55. The ratchet wheel 54 has two cams 56 and 57 turning therewith for operation of the plungers 58 of two limit switches S₂ and S₁, respectively, which, as will presently appear, are included in the electrical control system of the machine and are so illustrated in Fig. 12. The shaft 55 is not turned in the upward movement of the ram 33, inasmuch as such movement causes counterclockwise turning of the gear 51, and in such turning the pawl 53 rides idly over the teeth of the ratchet wheel 54. However, in the return stroke of the ram, when the gear 51 is given clockwise rotation, the pawl 53 operatively engages a tooth of the ratchet wheel and causes the shaft 55 to be turned through a predetermined angularity. A gear 55' keyed on the lower end of the shaft 55 turns with it and meshes with a gear 59 detachably secured on the lower end of a short vertical shaft 60 mounted in a bearing bushing 61 removably secured in a hole provided therefor in the spider 18, as by means of a set screw 62. A pinion 63 is fixed on the upper end of the shaft 60 and transmits intermittently drive to a ring gear 64, namely, in each return movement of the ram 33. The ring gear 64 forms part of a rotary work holder or support and has an upwardly projecting hub portion rotatable freely in a bearing 65 in the center of the spider 18. Two rings 66 and 67 are detachably fastened together and to the hub of the gear 64 above the bearing 65 so that they serve to support the gear 64. The ring 66 has a center hole 68 large enough to admit the lower end of the shell S freely but too small to allow the band B in its original uncompressed size to pass through, whereby to provide a support on top of the ring 66 for the band B prior to the operation of the machine to apply the band, the hole 68 being large enough to permit passage of the banded portion of the shell therethrough at the conclusion of the banding operation, so that the banded shells may be dropped down into a chute 69 for discharge from the machine. A swingable work support 70 is pivoted, as at 71, on the ring gear 64 and ring 67 and is normally held in the operative position, shown in Fig. 10, under the action of a coiled torsion spring 72 which encircles the pivot pin 71 and has one end fixed to the ring 64 and the other movable end fixed to the pivot pin 71. An arm 73 projects from the work support on the opposite side of the pivot 71 and is arranged to have slidable engagement with a cam 74 in the manner illustrated in Fig. 11 when the ring gear 64 is turned in its final indexing operation after the third squeeze. When the arm 73 slides along the

cam 14, the work support 70 is held in an out-of-the-way inoperative position, as shown in Fig. 11, allowing the banded shell S to drop by gravity into the chute 69 for discharge from the machine. The work support 70 is shown in Fig. 10 in its operative position at the commencement of the cycle, and, as will soon appear, after the first squeeze or partial squeeze the gear 64 is turned through approximately 120° in a counter-clockwise direction from the position of Fig. 10, so as to turn the shell with the partially compressed band thereon through one-third of a turn preparatory to the second squeeze. Then after the second squeeze the gear 64 is turned again through 120° so as to index the shell through another third of a turn preparatory to the third and final squeeze. This indexing of the work between squeezes, as previously pointed out, permits the metal to flow uniformly and crystallization is prevented, and the band is caused to grip the serrations with substantially the same tightness throughout its circumference. After the third and final squeeze the gear 64 is turned again through 120°, back to the original position shown in Fig. 10, and it is during that movement that the work support 70 is moved out of the way, as illustrated in Fig. 11, to allow the banded shell to drop out. It will, of course, be understood that we may dispense with the chute 69, where it is not desired to have the banded shells dropped into a container for fear of having the shells and bands thereon nicked by such handling, and in that event the only change necessary is to omit the cam 14 so that the work support 70 always remains in the operative position shown in Fig. 10. The operator in such event will, of course, have to remove the banded shells by hand. The cam 14 is supported on two spaced and substantially parallel vertical arms 15, which project upwardly from plate 76 removably secured onto the lower end of a stationary shaft 17, which extends upwardly through the tubular shaft 55 and is secured at its upper end, as at 18, in a boss 79 on a plate 80 fastened to the top of the guide 49. The shaft 17 has an annular flange 81 integral with the lower end portion thereof, and this flange forms a support for the lower end of a tubular shaft 55 and gear 55' keyed thereon. A screw 82 serves to fasten the plate 76 onto the lower end of the shaft 17, and when it is desired to remove the cam 14, this screw can be removed to allow the plate 76, carrying the cam, to be removed. Different thicknesses of shims 83 may be fastened on the upper face of the work holder 70 to support the shell at a higher or lower elevation, depending upon the spacing of the band receiving groove with respect to the lower end of the shell. In that way the machine can be easily adjusted to suit different requirements. The top plate 84, which is removably secured, as at 85, on top of the spider 18, has an enlarged center hole 86 through which the shells may be entered and in certain instances removed after banding. A cover 87 is shown in Figs. 1 and 7 to enclose the switches S₁ and S₃ and the other switches S₂, S₄, and S₅ and the moving parts of the machine associated therewith. The top plate 84 also forms a support for the guide 49 which is disposed inside the cover 87.

In Fig. 13 we have illustrated an expander type mandrel 88 insertible in the bore 89 of high explosive type shells, like that indicated at S', to support the thin walls of the shells and prevent distortion thereof in the application of bands thereto. It will be understood that although a

small portion of the machine is illustrated in this figure, the machine, except for the mandrel 88 and its cooperating plunger 90, is generally the same as that previously described, there being slides 20 movable radially inwardly in the spider 18 to cause the jaws 21 on the inner ends of these slides to compress the band B into the groove 14 in the shell, and there being also a ring gear 64' forming part of the work holder rotatable in the bearing 65 and arranged to be indexed between squeezes, similarly as the ring gear 64. The swingable work support 70, previously described, is, of course, eliminated, and also the cam 14 for operating the same, and instead of the rings 66 and 67 two rings 66' and 67' are provided, detachably secured together and to the ring gear 64' to support the latter against displacement downwardly from the bearing 65. The center hole 68' in the ring 66' is large enough to receive the lower end of the shell, which rests on a work supporting ring 91 fastened to the bottom of the ring 66'. The grooved portion 14 of the shell is thus exposed above the ring 66' in the plane of operation of the jaws 21 to receive the band B. The mandrel 88 is supported on the ring 91 to project up into the bore 89 slightly beyond the grooved portion of the shell. The plunger 90, which cooperates with the mandrel to expand it, is reciprocable and rotatable in the bore 92 of a tubular guide 93 carried on and projecting upwardly from a plate 41' detachably secured to the upper end of the ram 33. This plate corresponds to the plate 41 previously described, and has the rod 42 adjustably connected therewith, which has the rack 45 on the upper end thereof forming a part of the indexing mechanism. A coiled compression spring 94 is housed inside the guide 93 and tends normally to urge the plunger 90 upwardly for expansion of the mandrel 88. When the ram 33 is in its retracted position, as at the commencement and end of a cycle of squeeze operations, the spring 94 does not exert sufficient pressure on the plunger 90 to cause the mandrel 88 to grip the shell tightly, and there is, therefore, no appreciable interference with the easy removal and loading of work. However, it requires very little movement of the ram 33 upwardly on the working stroke to increase the spring pressure against the plunger 90 sufficiently for the mandrel 88 to grip the work tightly and thus provide ample support for the thin walls of the shell to prevent compression thereof in the compression of the band. On the other hand, there is no danger of the mandrel causing expansion of the shell, inasmuch as the plunger 90 is not operated positively but the spring 94 yields when the resistance to movement of the plunger 90 exceeds a predetermined amount. The operator can easily keep the mandrel 88 well lubricated, so that the plunger 90 can slide back and forth therein easily, and in that way there will be no likelihood of the mandrel seizing and thus interfering with easy removal of the banded shells. The mandrel in no way interferes with the easy indexing of the shell between squeezes, because it is in the retracting movements of the ram 33 that the indexing occurs and the spring pressure 94 against the plunger 90 is, therefore, reduced during the indexing operation, thus allowing the plunger 90 to turn freely with respect to its guide 93 if the mandrel 88 should not turn with respect to the plunger.

Referring now to Fig. 12 for a better understanding of the operation of the machine, an oil pump is shown at 95 arranged to be operated con-

tinuously by an electric motor 96 to serve as a source of oil under pressure. The oil is pumped from a sump 97, and so long as the plunger controlled valve V₃ is open, the oil is discharged idly back into the sump. To start the cycle of three squeeze operations, one soft and two hard, the operator closes switch S₇ to energize relays R₁ and R₂. The operator keeps the switch S₇ closed long enough for the ram 33 to rise far enough to close switch S₄. Valve V₄ is closed by reason of the energization of its solenoid by relay R₂. This causes valve V₃ to shift, closing its drain passage so that the full head of the pump 95 is delivered to valves V₂ and V₁. The closing of relay R₁ energizes the solenoid of valve V₁ causing its valve plunger to rise to the opposite extreme from that shown, so that fluid is delivered from valve V₁ to shift the plunger of valve V₂ to its lower extreme position, thereby delivering fluid under pressure to the bottom of the working cylinder 37 to raise the ram 33. The ram 33 will rise on its first stroke until it opens the limit switch S₂. The opening of switch S₂ opens relay R₁, and the plungers of valves V₁ and V₂ return to the positions shown, so that oil under pressure is delivered to the upper end of the working cylinder 37 for return of the ram 33. In this return movement of the ram the ratchet wheel 54 is operated to shift the control cams 56 and 57 through approximately 120°, thereby closing switches S₁ and S₃. From this point on the switch S₂ has no control over the operation of the machine to completion of the cycle, the two other squeezing operations being independent of the limit switch S₂ and controlled by the pressure switch S₆. When the ram 33 is stopped by reason of the work offering resistance to movement of the gripping jaws, pressure is built up in the cylinder 98 in which the plunger 99 for operating the pressure switch S₆ is disposed. This pressure is indicated on the gauge 100, and the operator can alter the pressure at which switch S₆ will be opened, to suit the work, by adjusting the plug 101 to increase or decrease the pressure of the spring 102 resisting movement of plunger 99. When the pressure is sufficient to overcome the resistance of the reacting spring 102, the switch S₆ will be opened. This, in turn, causes opening of the relay R₁ for the return stroke of the ram 33. The valves V₁ and V₂ return, as previously described, to the positions shown. In this second return movement of the ram, the ratchet wheel 54 is again turned through approximately 120° to index the two control cams 56 and 57 to a 240° position from that shown. When the ram 33 reaches the lower end of its stroke, switch S₅ is closed causing the closing again of relay R₁ and shifting of valve V₁ and consequent shifting of valve V₂ for the next upstroke of the ram. At the upper end of the stroke the ram 33 will again exert a pressure dependent upon the adjustment of the reacting spring 102 for the plunger 99 operating the pressure switch S₆, and when the switch S₆ is opened by the building up of pressure past a predetermined value, relay R₁ is again opened and valves V₁ and V₂ returned, as before, to the positions shown for the return stroke of the ram 33. In this downstroke, the ratchet wheel 54 is again indexed through approximately 120°, thus returning the control cams 56 and 57 to the position illustrated. The opening of the switches S₁ and S₃, along with S₄, completes the cycle and the machine stops. The work is then removed, if it has not been unloaded automatically, as previously described, and the machine is

then ready for the commencement of the next cycle.

It is believed the foregoing description conveys a good understanding of the objects and advantages of our invention. The appended claims have been drawn to cover all legitimate modifications and adaptations.

We claim:

1. In a shell banding machine, the combination of a frame having a plurality of radial guides provided thereon, slides working in said guides arranged to engage the work at their inner ends, said frame also having an axially extending guide, a ram working therein, a relatively movable piston and cylinder for operating the ram, a plurality of lever members pivotally supported on the frame intermediate their ends and operatively associated at one end with the slides and at the other end with the ram, wedge blocks on the ram, shoes pivotally mounted on the adjacent ends of the lever members and slidably engaging said wedge blocks, and spring pressed plungers on the frame having operative engagement with the lever members adjacent one end thereof to hold the shoes in close working contact with the wedge blocks, whereby the slides are operated positively in one direction by movement of the ram and are spring returned under operation of the plungers.
2. In a shell banding machine, the combination of a frame having a plurality of radial guides provided thereon, slides working in said guides arranged to engage the work at their inner ends, said frame also having an axially extending guide, a ram working therein, a relatively movable piston and cylinder for operating the ram, a plurality of lever members pivotally supported on the frame intermediate their ends and operatively associated at one end with the slides and at the other end with the ram, said ram having inclined cam surfaces provided thereon, shoes pivotally mounted on the adjacent ends of said levers slidably engaging said surfaces, and spring means for maintaining close working contact between said shoes and said surfaces, whereby the slides are operated positively in their work strokes by movement of the ram and are returned to retracted position under spring action.
3. A shell banding machine comprising a frame having a plurality of radial guides provided thereon, slides working in said guides arranged to engage the work at their inner ends, said frame also having an axially extending guide, a ram working therein, a relatively movable piston and cylinder for operating the ram, a plurality of lever members pivotally supported on the frame intermediate their ends and operatively associated at one end with the slides and at the other end with the ram, said ram having inclined cam surfaces provided thereon, shoes pivotally mounted on the adjacent ends of said levers slidably engaging said surfaces, spring means for maintaining close working contact between said shoes and said surfaces, a source of pressure fluid, a magnetically operated valve means controlling the supply of pressure fluid to said cylinder to advance and retract said ram, a ram travel limit switch, a pressure operated limit switch responsive to fluid pressure in said cylinder, means carried by said ram to actuate said ram travel limit switch, a rack gear on said last means, a pinion operated by said rack gear, a cycle control cam means actuated by said pinion, said ram travel limit switch and said pressure operated limit switch controlling the actuation of said magnetically

operated valve means to retract said ram, said cycle control cam means rendering said pressure actuated limit switch inoperative during an initial stroke of said ram and rendering said ram travel limit switch inoperative during subsequent strokes of said ram in a cycle of operation of the machine.
